UNITED STATES PATENT OFFICE

96,706

DESIGN FOR AN AMUSEMENT GAME CABINET

Vincent F. Slezak, Chicago, Ill., assignor to A. B. T.
Manufacturing Company, Chicago, Ill., a corporation of Illinois

Application February 25, 1935, Serial No. 55,605

Term of patent 7 years

To all whom it may concern:

Be it known that I, Vincent F. Slezak, a citizen of the United States of America, residing at Chicago, in the county of Cook and State of Illinois, have invented a new, original, and ornamental Design for an Amusement Game Cabinet, of which the following is a specification, reference being had to the accompanying drawing, forming a part thereof, and in which:

Fig. 1 is a perspective view of an amusement game cabinet showing my new design;

Fig. 2 is a sectional detail view of the same on line 2—2 in Fig. 1; and

Fig. 3 is a sectional detail view of the same on line 3—3 in Fig. 2.

I claim:

The ornamental design for an amusement game cabinet, as shown.

VINCENT F. SLEZAK.
